UNITED STATES PATENT OFFICE.

LEIGH S. BACHE, OF MIDDLESEX, NEW JERSEY, ASSIGNOR TO BOUND BROOK OIL-LESS BEARING COMPANY, OF BOUND BROOK, NEW JERSEY, A CORPORATION OF NEW JERSEY.

SADDLE FOR SPINNING-FRAMES.

1,200,434.

Specification of Letters Patent. Patented Oct. 3, 1916.

Application filed April 24, 1915. Serial No. 23,616.

To all whom it may concern:

Be it known that I, LEIGH S. BACHE, a citizen of the United States, and a resident of Middlesex, in the county of Middlesex and State of New Jersey, have invented certain new and useful Improvements in Saddles for Spinning-Frames, of which the following is a full, clear, and exact description, whereby any one skilled in the art may 10 make and use the same.

The invention pertains to spinning frames and particularly to certain new and useful improvements in top roll saddles which are employed upon the roll of spinning frames.

15 It pertains more particularly to a top roll saddle such as is used to hold the top rolls in contact with the drawing rolls of a spinning machine in a manner well known to those familiar with the art of spinning.

20 The object of the present invention is to provide an adjustable saddle in which the various elements of the saddle may be held together during the transposition and adjustment.

25 A further object is to provide a two-piece saddle with interconnections for readily swinging one saddle part with reference to the other without totally disconnecting the saddle members.

30 A still further object is to provide a swinging link connection between the upper and lower saddle members so that upon raising the tension weight on the upper saddle member, the lower saddle-part may be readily swung into a re-adjusted position upon the top rolls without liability of the saddle parts becoming separated and one or the other dropped.

Referring to the drawings: Figure 1 is 35 a side elevation of the saddle with the top rolls diagrammatically illustrated in position for spinning short-fibered staple. Fig. 2 is a similar view illustrating the saddle adjusted upon the rolls for spinning long-fibered staple. Fig. 3 is a perspective view 45 of the top saddle member. Fig. 4 is a similar view of the bottom saddle member. Fig. 5 is a sectional view illustrating a form 50 of link for uniting the upper and lower saddle members. Fig. 6 is a similar view of a slightly modified form of link. Fig. 7 illustrates a link interiorly arranged with reference to the two saddle members.

A two-piece saddle for spinning frames is, of course, not new in the art nor is it new 55 to provide for longitudinal adjustment of one saddle member with reference to the other so that the parts may be shifted to drop out the center roll, as is the case where long-fibered staple is being spun. It is likewise old in the art to provide such an adjustment as will permit the same saddle parts being used for three rolls as is the case where short-fibered staple is being spun. In devices of this character, particularly of the two-piece type, it is frequently necessary to readjust the saddle from a three-roll contact to a two-roll contact and as the operatives are generally of a class who are liable to make errors in the adjustments, it is a common occurrence for the saddles to be improperly placed on some of the rolls of a spinning frame. Furthermore, in changing one saddle member with reference to the other in longitudinal adjustment, the tension weight must be raised and the top saddle member moved in order to get at the lower saddle member, which straddles two of the rolls. Where the saddles are made in two parts, the operator is 65 further liable to drop the lower saddle member in attempting to raise the upper member and make the necessary change for adjustment.

It is one of the primal objects of the present invention to provide in conjunction with all of the ordinary well known longitudinal adjusting features of a two-piece saddle, a connecting device between the saddle parts so that one cannot be inadvertently dropped 70 when the other is raised and so that there will be one of two positions to which the lower saddle member may be shifted while still attached to the top saddle member. When the operative wishes to change from 75 the adjustment by dropping out the center roll, it is only necessary to raise the weighted top saddle member and push the lower member back to the limit of its play, whereupon it will seat itself in proper position 80 without bearing upon the center roll. Likewise, if the frame is running with the center rolls dropped out, it is only necessary to raise the top saddle member and shift the bottom member forward to the limit of its 85 play, whereupon the three rolls will be 90

brought into action. This is all accomplished without any liability of dropping one or the other of the members of the saddle and insures proper positioning of the saddle members.

In the accompanying drawings, 1, 2 and 3 denote the top rolls and 4, 5, 6 the corresponding drawing rolls of a given set upon a spinning frame. These are suitably mounted in bearings not specifically shown herein. The rolls 2, 3 represent the back-rolls and 1 the forward roll of a set. Upon the back rolls 2, 3, as illustrated in Fig. 1, rests the saddle member 7 and this is provided with a bearing surface 8 for the roll 3 and a surface 9 for the roll 2. The upper portion of the saddle member 7 is channeled as at 10 and into this channel projects a rib 11 formed on the under side of the tail of the top saddle member 12. This saddle member 12 has a bearing surface 13 for the front roll 1. The channel 10 and rib 11 form a convenient means for preventing lateral separation of the saddle members and the shoulders 14^a, 15^a at either side of the rib 11 are formed to extend beyond the side walls 16 of the rib 11 and overlie the walls 14, 15, of the channel 10.

The upper saddle member 12 is provided with an adjustable plate 17 which may be moved along the upper side of the member 12 and secured in place by a suitable screw or other clamping device 18. The tension stirrup 19 rests upon the forward end of the plate 17 and is held against longitudinal movement thereon by the up-turned end 20 and upset lug 21.

Between the top saddle member 12 and lower saddle member 7, there is arranged a hinged connection which, as illustrated in Figs. 1 to 5 of the drawings, consists of a bail or loop 22 which projects into transverse openings 23, 24 in the sides of the respective members 12 and 7. One of the perforations, as, for instance, the upper one 23, is preferably slightly elongated to give freedom of movement and adjustment between the saddle members. The length of the bail or connecting link 22 is such that when the lower saddle member is brought forward toward the head roll, 1, its bearing surfaces 9, 8 will register with the rolls 2 and 3. As the lower member is shifted rearwardly, it may be swung until a surface 8^a registers with the roll 3 and thereupon the roll 2 is cleared. It will be seen from this that by raising the upper saddle member 12 a slight distance, the lower member 7 may be swung backward and forward to a position for engaging both the rolls 2 and 3 for spinning a short-fibered staple or to a position engaging simply the back roll 3 for spinning long-fibered staple and that during this shifting, there is no liability of dropping the lower saddle member. In Fig.

5, a method of attaching the bail is illustrated, in which tubular members 25 are passed through the perforations 23 and 24. Two U-shaped bail-like members 26 are then inserted on opposite sides in the tubes and driven firmly together. This forms a convenient means of forming the necessary hinged joint between the two parts of the saddle and insures freedom from cramping as the parts are assembled, inasmuch as the U-shaped wires may be driven down to the ends of the small metallic tubes without cramping against the sides of the saddle members.

In Fig. 6, in lieu of using the tubes, a pair of connecting members 27 are illustrated, each having a long arm 28 which may project through the perforation of one saddle member and be riveted down as at 29 and with its opposite end in the form of a short parallel pivot 30. The use of this sort of connection necessitates two perforations in each of the saddle members.

In Fig. 7, there is illustrated a form of connecting hinge which is simple and most efficacious and is arranged entirely within the structure of the saddle blocks. This consists of a link 31 having an elongated perforation 32 at one end and a pivot perforation 33 at the opposite end. The central portion of the lower saddle member is grooved out as at 34 from the top and the lower side of the upper saddle member is grooved out as at 35 from the bottom. The link 31 is inserted in the grooves and pins 36, 37 are passed through the respective saddle members engaging the perforations 32, 33. In this form of the device, it will be noted that the hinged joint is formed interiorly of the structure where it is free from liability of becoming foul with lint or dirt and where it is not likely to be disarranged.

Of course, it is quite immaterial what exact form of connection is made between the two saddle parts so long as they are so hinged together that without transposing either of the parts, one may be swung with reference to the other to adjust, as may be desired for two or three rolls or more, as the case may be.

It will be observed that there is no change in all the advantageous features of a saddle block which embodies relative longitudinal adjustment, insurance against transverse displacement and proper tensioning. With all these features present, there is the additional advantage of being able to shift and adjust the members relatively to each other with precision and without liability of dropping and mis-placement of either of the members.

In practice, it is preferred to make the saddle members 12 and 7 from a treated fiber which has a homogeneous character and is self-lubricating as to its entire structure.

but, of course, the adjusting feature may be applied to any desired form of two-piece saddle.

What I claim as my invention and desire to secure by Letters Patent is:

- 5 2. A saddle for spinning frames comprising a top saddle and bottom saddle adjustably mounted with reference to each other and permanently interconnected by a link 10 member pivoted to each saddle member whereby one saddle member may be shifted longitudinally into either one of two positions for adjustment with reference to the other without disengagement of the parts.
- 15 2. A saddle for spinning frames comprising two parts having free longitudinal movement with reference to each other and a link pivotally connected with both of said parts, though permitting longitudinal adjustment thereof as one is swung with reference to the other, said connecting link determining the amount of adjustment between the saddle parts as they are relatively moved into either one of two positions of 20 adjustment.
- 25 3. A saddle for spinning frames comprising two parts having interengaging members between the saddle parts permitting longitudinal adjustment thereof, recesses in the meeting engaging portions of both parts 30 and a pivoted link arranged in said recesses and pivotally connected to both of the saddle parts, though permitting longitudinal adjustment thereof into two definite positions as one is swung relatively to the other 35 upon the pivoted link.
4. A saddle for spinning frames comprising two parts, one normally resting upon the other and relatively adjustable into either one of two positions, recesses in the 40 engaging portions of both parts and a pivoted link arranged in said recesses and pivotally connected to both of the saddle parts, though permitting longitudinal adjustment thereof as one is swung relatively to the 45 other upon the pivoted link.
